UNITED STATES PATENT OFFICE

ALFRED W. F. GUEST, OF BROOKLYN, NEW YORK, ASSIGNOR TO MERGENTHALER LINOTYPE COMPANY, A CORPORATION OF NEW YORK

TYPOGRAPHICAL COMPOSING MACHINE

Application filed July 3, 1930. Serial No. 465,518.

This invention relates to typographical composing machines, such as linotype machines of the general organization represented in U. S. Letters Patent to O. Mergenthaler No. 436,532, wherein circulating matrices are released from a magazine in the order in which their characters are to appear in print and then composed in line, the composed line transferred to the face of a slotted 5 mold, the mold filled with molten metal to form a slug or linotype against the matrices which produce the type characters thereon, and the matrices thereafter returned through distributing mechanism to the magazine from which they started.

In these machines, the matrices, as they are released from the magazine, descend by gravity through a channeled raceway and fall onto the upper stretch of an inclined conveyor belt which delivers them, one after another, to a chute or throat whereby they are directed into the assembler or assembling elevator. As the matrices enter the assembler, they are stacked side by side in line, under the influence of a rapidly rotating star wheel, against an upstanding finger or line resistant secured to one end of the yielding assembler slide.

To insure the proper composition of the 30 matrices, it is important that they be maintained under positive control as they enter the assembler. For this reason, the lower end of the chute spring, which constitutes the upper wall of the assembler chute, is arranged 35 to prevent upward displacement of the matrices as they enter the assembler, and the opposite side walls of the assembler are spaced apart at a distance corresponding to the width of the matrices so as to prevent their 40 edgewise displacement after they enter the assembler, the latter also being provided with means to hold the matrices upright therein and from falling back against the star wheel or into the path of succeeding matrices. 45 However, the arrangement of the parts is such that each matrix enters the assembler foot-first at an inclination and, unless interrupted by the star wheel, strikes with considerable force against the exposed side face of 50 the matrix last composed in the zone which

contains the matrix cavities or characters. As a result of this impact, which is particularly severe in the case of the thick or heavier matrices, the thin side walls of the matrix characters are frequently crushed or 55 damaged after a relatively short period of use, and the matrices thus mutilated have to be discarded.

The present invention is intended to obviate this and other difficulties and in a manner which involves little or no change in the general structure of the assembler or other parts of the assembling mechanism. To this end, specifically, it is proposed to displace or offset the assembler bodily rearward at its 60 receiving end with respect to the line of delivery of the matrices, so that the character side walls of matrices already composed in line will stand out of the path of matrices that follow, and to provide means at the entrance of the assembler for deflecting the individual matrices edgewise rearwardly as they are delivered thereto so as to direct them 65 into the straight parallel-sided composing channel.

In the accompanying drawings, the invention has been shown merely in preferred form and by way of example, but obviously many changes and variations may be made 70 therein and in its mode of application which will still be comprised within its spirit. It should, therefore, be understood that the invention is not limited to any specific form or embodiment, except in so far as such limitations are specified in the claims.

Referring to the drawings:

Figure 1 is a front elevation of the assembling mechanism, having the present improvements embodied therein;

Fig. 2 is a plan view, partly in section, of the parts shown in Fig. 1;

Fig. 3 is an enlarged perspective view of the receiving end of the improved assembler; and

Fig. 4 is an edge view of an ordinary two-letter linotype matrix.

The matrices X, when released from their storage magazine (not shown), pass downwardly through a channeled raceway and onto a constantly driven inclined belt A (Fig. 106

1), which latter discharges them one after another in the order of their release into a throat or chute B leading to the assembler C. Here they are composed in line against the upstanding finger D¹ of a line resistant slide D under the influence of a rapidly rotating star wheel E which crowds them forward against the end of the line and at the same time advances the latter to admit the next or following matrix. In passing through the chute B, the matrices are caused to follow the fixed lower curved side wall B¹ by the yielding upper wall or chute spring B². The assembler C is slidably mounted for vertical movement in fixed guides or gibs O¹, O² secured to the front plate O and arranged to engage tongues c formed at the rear side of the assembler C and at the opposite ends thereof. After composition of the line, the assembler is raised to carry the line up between the depending fingers (not shown) of a line delivery slide, which thereupon shifts the line horizontally from the assembler through the intermediate channel F to the casting mechanism.

The assembled C, as will be noted (Fig. 2), presents a straight, parallel-sided channel C¹ wherein the matrices are composed in line and which is constituted generally by the front and rear side walls C², C³, respectively, and the longitudinally extending rails C⁴ upon which the matrices are supported by their lower projecting ears x¹. Matrices in the course of composition undergo considerable agitation by the action of the star wheel E as they pass from the chute B, and in order to cope with this condition, the lower end of the chute spring B² is provided with horizontal deflecting surfaces B³ adapted to prevent the matrices from being thrown upwardly and outwardly over the line. The parallel side walls C², C³, of the assembler channel C¹ overlap the star wheel E and hence guide the matrices by their opposite edges and support them in upright position after they enter the line. The tendency of the matrix last assembled to fall back toward the star wheel, where it would likely interfere with the next succeeding matrix, is overcome by the use of pawls C⁵, C⁶, resiliently mounted at the receiving end of the channel C¹ upon the opposite side walls C², C³. These pawls cooperate with the individual matrices in the customary way and are intended to snap in behind the upper projecting ears x² thereof as the matrices are pushed ahead by the star wheel E.

So far as described, the parts, their construction and mode of operation, except as hereinafter pointed out, are or may be the same as those embodied in the commercial linotype machine, and in themselves constitute no part of the present invention.

Ordinarily, the assembler C is mounted in the gibs O¹, O², so that the center line of

the channel C¹ is coincident with the center line a—a (Fig. 2) of the chute E and the intermediate channel F. In carrying out the present invention, however, the assembler channel C¹, as will also be noted from Fig. 76 2, is displaced rearwardly with respect to the center line a—a so as to locate the rear side wall C³ at the receiving end of the channel in offset relation to the rear wall of the chute B. This offset relation of the parts is accomplished by recessing or reducing the height of the finished surface o of the front plate O to which the right guide or gib O² (Figs. 1 and 2) is secured, the other gib O¹ being preferably undisturbed so that the customary relation between the opposite end or exit of the channel C¹ and the intermediate channel F may be retained. The assembler C will thus stand at a slight rearward inclination to the front plate O, and the matrices supported in the channel C¹ thereof will in consequence have the thin side walls of their characters x disposed out of the path of succeeding matrices entering the channel (see Fig. 2). The engaging face d of the line resistant finger D¹ is also inclined or slanted so as to stand in a plane perpendicular to the opposite walls of the assembler C and thus to present a square banking surface to the leading matrix of the composed 95 line.

To compensate for the offset relation of the assembler channel C¹ to the chute B, means are provided for deflecting the individual matrices edgewise rearwardly so as to direct them into said channel as they are delivered thereto. In the preferred embodiment illustrated, such means comprise beveled surfaces C⁷, C⁸, formed on the front wall C² of the assembler C, although they might be otherwise formed or located. The beveled surface C⁷ (see Fig. 3) is formed on the front retaining pawl C⁵ and is adapted to cooperate with the upper projecting ears x² of the matrices, while the beveled surface C⁸ is formed directly on the front side wall C² immediately below the deflecting surface C⁷ and is adapted to cooperate with the lower projecting ears x¹ of the matrices.

The arrangement of these beveled surfaces C⁷, C⁸, is such that, as the individual matrices pass edgewise from the chute B, their lower projecting ears x¹ first engage the lower beveled surface C⁸ and then, as the matrices are pushed ahead by the star wheel E and held downwardly by the horizontal surface B³ of the chute spring B² their upper projecting ears x² are caused to engage the upper beveled surface C⁷ of the pawl C⁵. Both beveled surfaces C⁷, C⁸, act substantially conjointly in deflecting the individual matrices edgewise rearwardly as they are advanced by the star wheel E, which thus not only furnishes the motive power for deflecting the matrices but which also shoves them forward into the

assembler channel after their deflection or along with it. As the matrices are stacked successively in line, the retaining pawls C⁵, C⁶ snap behind their upper projecting ears and prevent them from falling out.

It will now be seen that, by reason of the peculiar form and arrangement of the parts, the thin character side walls of the matrices previously composed in the assembler channel C¹ are fully protected from the damage ordinarily caused by the impact of the following matrices, and this in a way which will allow the matrices to follow one another into the line with consistent regularity and with little danger of clogging the assembling mechanism. In other words, the blow from a thick or heavy matrix descending through the chute B (see Figs. 1 and 2), is absorbed by the preceding matrix as usual but it is struck at a point forwardly of the thin side walls of the characters α . The same is true of all the matrices, but the relatively light blow of the thinner ones will be broken and almost completely absorbed alone by the beveled surfaces C⁷, C⁸. To be more explicit, since the projecting ears of all matrices throughout a font, as is well-known, are generally located at that side upon which the matrices lie during their travel to the assembler, the bodies of the thicker matrices, as they enter the assembler channel C¹ foot-first, will strike the preceding matrix of the line before their lower projecting ears engage the deflecting surfaces C⁷, C⁸, but due to the offset relation of the said channel to the line of delivery, the striking point will be forward and clear of the character side walls of the last assembled matrix, so that no damage can result. While it is these thicker matrices that in practice cause the greatest damage because of their excessive weight and the momentum they possess at the time they enter the assembler, the character side walls of assembled matrices are also protected from the impact of the thinner matrices, since the lower projecting ears of the latter matrices will engage the deflecting surfaces C⁷, C⁸, before their body portions (on account of being so thin) strike the last assembled matrix. The desired protection of the delicate side walls of matrix characters is thus carried out to the maximum degree and irrespective of the thicknesses of the matrices handled.

Having thus described my invention, what I claim is:

1. In a matrix composing machine, the combination of an assembler presenting a channel wherein the matrices are composed in line, said channel thruout its length having straight parallel sides, means for delivering the matrices successively to the assembler channel, said channel being displaced with respect to the line of delivery of the matrices, and means for deflecting the individual

matrices edgewise to direct them into the assembler channel as they are delivered thereto.

2. In a matrix composing machine, the combination of an assembler presenting a channel wherein the matrices are composed in line, said channel thruout its length having straight parallel sides, means for delivering the matrices successively to the assembler channel, said channel being displaced rearwardly so as to position its receiving end in offset relation to the line of delivery of the matrices, and means for deflecting the individual matrices edgewise rearwardly so as to direct them into the assembler channel as they are delivered thereto. 70

3. In a matrix composing machine, the combination of an assembler having straight parallel front and rear side walls and longitudinally extending matrix supporting rails, a chute for delivering the matrices successively to the assembler, said assembler and chute having their center lines offset with relation to each other so as to position the rear wall of the chute forwardly of the straight rear wall of the assembler, and means for deflecting the matrices edgewise rearwardly to direct them from the chute into the assembler. 75

4. In a matrix composing machine, the combination of an assembler wherein the matrices are composed in line and presenting inner side walls straight and parallel thruout, a chute for delivering the matrices successively to the assembler, a channel into which the composed line is transferred from the assembler as a whole, said assembler being inclined with respect to a center line common to both the chute and channel such that the receiving end of the assembler is positioned in offset relation to the discharge end of the chute, and means for deflecting the individual matrices edgewise to direct them into the assembler as they are delivered thereto. 80

5. In a matrix composing machine, the combination of an assembler having front and rear side walls straight and parallel thruout and longitudinally extending matrix supporting rails, a chute for delivering the matrices successively to the assembler, a channel into which a composed line of matrices is transferred from the assembler as a whole, said assembler being inclined rearwardly with respect to a center line common to both chute and channel such that the rear wall of the assembler at the receiving end thereof is positioned rearwardly of the rear wall of the chute, and means for deflecting the individual matrices edgewise rearwardly to direct them into the assembler as they are delivered thereto. 85

6. A combination as specified in claim 5, characterized by the fact that the deflecting means therein referred to are constituted by beveled surfaces located on the front side wall 130

of the assembler at the receiving end thereof.

7. In a matrix composing machine, the combination of an assembler having straight parallel front and rear side walls and longitudinally extending matrix supporting rails, means for delivering the matrices successively to the assembler, said assembler being displaced with respect to the line of delivery of the matrices, and two beveled surfaces located on the front wall of the assembler and arranged to cooperate respectively with the upper and lower projecting ears of the individual matrices so as to deflect them edgewise into the assembler as they are delivered thereto.

8. A combination as specified in claim 7, characterized by the fact that the assembler is provided with a matrix retaining pawl resiliently mounted on the front side wall thereof, and that one of the beveled surfaces therein referred to is formed on said pawl and adapted to cooperate with the upper projecting ears of the individual matrices, while the other beveled surface is formed directly on said wall and adapted to cooperate with the lower projecting ears of the matrices.

9. In a matrix composing machine, the combination of an assembler wherein the matrices are composed in line and presenting inner side walls straight and parallel throughout, means for delivering the matrices successively to the assembler as a whole, said assembler being displaced laterally with respect to the line of delivery of the matrices, and deflecting members arranged to cooperate respectively with the upper and lower projecting ears of the individual matrices so as to direct them edgewise into the assembler as they are delivered thereto.

10. A combination as specified in claim 9, characterized by the fact that the assembler therein recited is inclined rearwardly in a horizontal direction so as to displace its receiving end with respect to the said line of delivery of the matrices, for the purpose described.

11. In a matrix composing machine, the combination of an assembling elevator wherein the matrices are composed in line and presenting inner side walls straight and parallel throughout, a chute for delivering matrices to said elevator, and a pair of fixed vertical guideways wherein the elevator is slidably mounted, said guideways being arranged respectively at the opposite ends of the elevator and positioned in different vertical planes so as to locate the receiving end of the assembling elevator in offset relation to the discharge end of the chute, for the purpose described.

12. In a matrix composing machine, the combination of an assembler having front and rear side walls, a chute for delivering the matrices to the assembler, said assem-

bler and chute being offset with relation to each other so as to position the rear wall of the chute forwardly of the rear wall of the assembler, a yielding line resistant finger associated with the assembler, a star wheel for stacking the matrices successively in line against the finger, and beveled surfaces arranged to cooperate respectively with the upper and lower projecting ears of the matrices for deflecting them edgewise rearwardly as they are stacked in line.

13. A combination as specified in claim 12, characterized by the fact that the side walls of the assembler therein recited are straight and parallel but inclined rearwardly toward the receiving end of the assembler, and that the matrix sustaining face of the said line resistant finger is perpendicular to the side walls of the assembler.

14. In a matrix composing machine, the combination of an assembler wherein the matrices are composed in line, means for delivering the matrices successively to the assembler, said assembler being displaced with respect to the line of delivery of the matrices, means for deflecting the individual matrices edgewise to direct them into the assembler as they are delivered thereto, and means for restraining the matrices against forward edgewise displacement as they enter the line.

15. A combination as specified in claim 1, including a pair of pawls mounted on the respective straight parallel side walls of the assembler channel for preventing the matrices from falling out after they enter the channel.

16. A combination as specified in claim 1, including a chute spring for preventing the upward displacement of the matrices as they enter the assembler channel.

In testimony whereof, this specification has been duly signed by:

ALFRED W. F. GUEST.
